MECHANICAL GOLF PLAYER'S STANCE POSITIONER

James Rikuo Hara, Honolulu, Territory of Hawaii

Application May 16, 1950, Serial No. 162,283

3 Claims. (Cl. 273—35)

1

This invention relates to devices for instructing golf players, and in particular a mechanical device for positioning different parts of the body and for holding the body in the proper stance for swinging a golf club.

The purpose of this invention is to provide a mechanical device that holds the different parts of the body in the correct position whereby the correct swing and follow through of a golf player are obtained.

Mechanical devices have been provided for holding the head and also for showing the position of the feet of a golf player but in order to give the body the correct stance it has been found desirable to provide elements for holding different parts of the body. With this thought in mind this invention contemplates a telescoping post mounted on a stand having stance indicating means thereon with hip pads adjustably mounted on the post, with a head engaging element extended from the upper end of the post, and with a shoulder blade bar and straps adjustably mounted on the arm by which the head engaging element is adjustably attached to the upper end of the post.

The object of this invention is, therefore, to provide a universal mechanical position holding device for golf players that indicates the correct position of different parts of the body.

Another object of the invention is to provide a stance indicator for golf players that is readily adjustable to players of different sizes.

A further object of the invention is to provide a golf player stance positioning device which is of a simple and economical construction.

With these and other objects and advantages in view the invention embodies a stance indicator having body engaging elements adjustably mounted on a telescoping post and means permitting swinging action of the said body engaging elements as the player swings a golf club.

Other features and advantages of the invention will appear from the following description taken in connection with the drawings wherein:

Figure 1 is a side elevational view illustrating the parts of a mechanical stance positioning device as they appear in use on a player with the player shown in dotted lines.

Figure 2 is a plan view of the base of the stance positioner taken on line 2—2 of Figure 1.

Figure 3 is a sectional plan showing the grip positioning elements being taken on line 3—3 of Figure 1.

Figure 4 is a detail showing a section on line 4—4 of Figure 3 with parts broken away and

2

showing the resilient mounting of traveling blocks therein.

Figure 5 is a detail showing a section taken on line 5—5 of Figure 3 illustrating one of the hip mounting pads.

Figure 6 is a cross section taken on line 6—6 of Figure 3 showing the adjustable bars for holding the hip positioning pads.

Figure 7 is a cross section taken on line 7—7 of Figure 1 showing the collar bone brace bar.

Figure 8 is a cross section taken on line 8—8 of Figure 7 showing the adjustable ends of the collar bone brace bar.

Figure 9 is a plan view taken on line 9—9 of Figure 1 showing the head engaging band.

Referring now to the drawings wherein like reference characters denote corresponding parts the improved golf player stance positioner of this invention includes a telescoping post having a rod 10 slidably in a tubular base section 11, a base 12 having laterally extended arms 13 and 14, a hip positioner including pads 15 and 16 carried by an arm 17, a shoulder blade brace 18 carried by an L-shaped arm 19, and a head plate 20.

The post 10 is slidably mounted in the tubular base section 11 and a thumb screw 21 is provided in the base section for retaining the post in adjusted positions. The lower end of the section 11 is provided with a T-shaped head 22 through

30 which the rod 12 forming the base extends. One end of the rod 12 is provided with a supporting plate 23 and a bar 24 on the opposite end is provided with an arcuate shoe 25 that indicates the swing arc of a club. The shoe 25 is attached to the bar 24 by screws 26 and 27 and corresponding threaded openings 28 and 29 are provided in the opposite end of the bar whereby the shoe 25 may be positioned on the opposite side for a left hand player.

40 A stance indicating bar 30 is pivotally attached to the base 12 by a screw 31. This bar is set to engage the toes of the shoes of a player to indicate the correct positions of the feet.

The arm 17 on which the hip pads 15 and 16 are positioned is pivotally attached through a projection 32 to a horizontally disposed arm or bar 33 by a thumb screw 34 and the bar 33 extends outwardly from a tube 35 that is mounted in a yoke having horizontal tubular members 36 and 37 and vertically disposed members 38 and 39. The ends of the tube 35 are provided with balls 40 which are positioned in sockets in the ends of cylindrical blocks 41 and 42 and these blocks are resiliently held by springs 43 and 44 whereby the balls are urged to center positions

in the horizontal members 36 and 37 of the yoke. The yoke is adjustably mounted on the post 10 by arms 45 and 46 which extend outwardly from a sleeve 47 and the sleeve is secured in position by a thumb screw 48.

The tube 35 on which the hip engaging pads 15 and 16 are supported is also provided with L-shaped arms 49 and 50, the outer ends of which are provided with adjusting screws 51 and 52 and the adjusting screws are positioned to engage the side surfaces of the sleeve 47 to limit lateral movement of the hips through the hip engaging pads.

The hip engaging pads 15 and 16 are carried by arcuate bars 53 in slots 54 in the ends of the bar 17 and the bars 53 are adjustably held by thumb screws 55 that extend through slots 56 therein. The pads are secured to the bars 53 by thumb screws 57 and loops 58 are provided on the ends of the bars for straps 59 and 60, with the strap 60 extended from the pad 15 and the strap 59, which is provided with a buckle 61, extended from the pad 16.

The shoulder blade brace 18 is provided with a socket 62 by which it is adjustably mounted on the end of the L-shaped arm 19 and the socket is retained on the arm by a cotter pin 63. The arm 19 is mounted through a hub 64 at the inner end thereof on a bar 65 and the hub is provided with a thumb screw 66. The bar 65 is pivotally attached to a bar 67 by a pin 68 and the bar 67 is slidably mounted in a T-fitting 69 on the upper end of the post 10, the fitting 69 being provided with a thumb screw 70 and providing a swivel connection whereby the bar 67 is positioned in different angles in relation to the post 10.

The head plate 20 is pivotally mounted on the end of the bar 65 by frictionally connected arms 71 and 72 which extend from a hub 73 and the plate is held on the bar 65 by a thumb screw 74. The arms 71 and 72 are connected by a friction pin 75, and the head plate 20 is connected to the outer end of the arm 71 by a similar friction pin 76 which is positioned in a lug 77 extended upwardly from the head plate.

The shoulder blade brace 18 is also provided with extensible ends having tips 78 and 79 carried on the ends of bars 80 and 81 respectively and the bars are slidably mounted in slots 82 and 83 in the ends of the brace. The bars are adjustably secured in the ends of the brace by thumb screws 84 and 85 and the ends of the tips 78 and 79 are provided with eyes 86 and 87 from which straps 88 and 89 extend, respectively.

With the parts arranged in this manner the stance is adjusted to correspond with the hips, shoulder blades, and head of a golf player and the parts hold the player in the correct position for swinging a club, as indicated by the dotted lines 90 to strike a ball as indicated at 91. The parts have sufficient freedom of movement to permit natural movement of the different parts of the body in making the swing and at the same time prevent the player moving out of position.

It will be understood that modifications may be made in the design and arrangement of the parts without departing from the spirit of the invention.

What is claimed is:

1. In a golf player stance positioner, the com-

bination which comprises a telescoping post, a base having a foot positioning bar pivotally mounted thereon and upon which the said post is mounted, an arcuate shoe positioned on the base indicating the line of flight and swing arc, a horizontally disposed rectangular shaped frame adjustably mounted on the post, arms having hip engaging pads adjustably mounted on the ends thereof suspended from the said rectangular shape frame, yielding means in the frame providing lateral movement of the hip pad carrying arms, spaced arms extended from said hip pad carrying arms and positioned to contact the telescoping post to limit lateral movement of the said hip pad carrying arms.

2. In a golf player stance positioner, the combination which comprises a telescoping post, a base having a foot positioning bar pivotally mounted thereon and upon which the said post is mounted, a horizontally disposed rectangular shaped frame adjustably mounted on the post, a vertically disposed tubular rectangular shaped section carried by said horizontally disposed rectangular shaped frame and spaced from said post, arms having hip engaging pads adjustably mounted on ends thereof suspended from said vertically disposed tubular frames, resilient means in the tubular elements of the vertically disposed rectangular shaped frame providing lateral movement of the hip pad carrying arm, and spaced arms extended from said hip pad carrying arms and positioned to contact the telescoping post to limit lateral movement of the said hip pad carrying arms.

3. In a golf player stance positioner, the combination which comprises a telescoping post, a base having a foot positioning bar pivotally mounted thereon and upon which the said post is mounted, a horizontally disposed rectangular shaped frame adjustably mounted on the post, a vertically disposed rectangular shaped tubular frame carried by said horizontally disposed frame, a vertically positioned tube positioned with ends thereof extended into elements of the vertically positioned tubular frame, springs in tubular elements of the vertically positioned tubular frame for urging the vertically positioned tube to a position in the center of the frame, arms having hip engaging pads adjustably mounted on extended ends thereof suspended from the vertically disposed tube, said springs providing lateral movement of the hip pad carrying arms, and spaced arms extended from said vertically disposed tube and positioned to contact opposite sides of the telescoping post to limit lateral movement of the said vertically disposed tubes and hip pad carrying arms.

JAMES RIKUO HARA.
